CLAIM

The ornamental design of a tablet computer, as shown and described.

DESCRIPTION

FIG. 1 is a top, left, back, perspective view of a tablet computer illustrating my new design;

FIG. 2 is a top view thereof;

FIG. 3 is a bottom view thereof;

FIG. 4 is a left side elevation view thereof;

FIG. 5 is a right side elevation view thereof;

FIG. 6 is a front side elevation view thereof;

FIG. 7 is a back side elevation view thereof;

FIG. 8 is a top, right, front, perspective view thereof;

FIG. 9 is a bottom, right, back, perspective view thereof; and,

FIG. 10 is a bottom, left, front, perspective view thereof. The broken lines in the drawings represent portions of the tablet computer that form no part of the claimed design.

1 Claim, 10 Drawing Sheets(56)
